UNITED STATES PATENT OFFICE

2,032,326

OSCILLATORY MOTOR

George H. Leland, Dayton, Ohio, assignor to The
Leland Electric Company, a corporation of
Ohio

Application November 10, 1930, Serial No. 494,570

37 Claims. (Cl. 172—126)

This invention relates to an automatic circuit breaker and closer and more particularly to a circuit breaker and closer of the type employed for causing the circuit to be closed through one or more lights at predetermined intervals and which is commonly known as a flasher. In devices of this kind in which the circuit breaking and closing element comprises a mercury tube switch, which is moved in one direction by electrically operated means and is moved in the other direction independently of the electrically operated means, it is necessary to retard or so regulate the movement of the circuit breaking and closing element as to provide a relatively slow and uniform movement thereof. Heretofore it has been customary to employ a dash pot for this purpose but this has not been entirely satisfactory because it has been found impractical to prevent all leakage of fluid from the dash pot and after a more or less extended operation the retarding action of the dash pot will vary and the timing of the circuits will be altered.

One object of the present invention is to provide improved means for regulating the return movement of the circuit breaking and closing element in an automatic circuit breaker and closer.

A further object of the invention is to provide an automatic circuit breaker and closer of this character in which the movements of the circuit breaking and closing element will be regulated by an inertia controlled device.

A further object of the invention is to provide a circuit breaker and closer of this type which will be simple in its construction, and which will operate indefinitely without variation in the timing of the circuits.

Other objects of the invention will appear as the device is described in detail.

In the accompanying drawings Fig. 1 is a front elevation of a circuit breaker and closer embodying my invention; Fig. 2 is a top plan view of the same; Fig. 3 is a section taken on the line 3—3 of Fig. 1; Fig. 4 is a rear view showing the cushioning device; Fig. 5 is a detail view of the arm which acts on the cushioning device; Figs. 6, 7, 8 and 9 are detail views of different forms of mercury tube switches which may be used in the apparatus; and Fig. 10 is a circuit diagram.

In these drawings I have illustrated one embodiment of my invention and have shown the same in connection with a switch for controlling lamp circuits but it will be understood that this particular embodiment has been chosen for the purposes of illustration only and the device may take various forms and may be used for various

purposes without departing from the spirit of the invention.

In carrying out my invention I provide a tiltable circuit breaking and closing element, preferably a mercury tube switch, which is moved in one direction by suitable electrically operated means and is moved in a reverse direction independently of said electrically operated means, this return movement being preferably effected either partly or entirely by gravity. Connected with the tiltable circuit breaking and closing element for movement in unison therewith is an inertia element which regulates the movement of the circuit making and breaking element in such a manner that these movements are effected at relatively slow speed and with absolute uniformity. The apparatus may take various forms and the inertia element may be actuated either directly by the electrically operated means, and thus constitute the driving element for the circuit breaking and closing element, or it may be independent of the electrically operated means.

In that particular embodiment here illustrated the circuit breaking and closing element comprises a mercury tube switch 10 having, in the present instance, three contacts, as shown at 11, 12 and 13. This mercury tube switch is mounted in clips 14 carried by a supporting member 15 which is here shown as an arm pivotally mounted at one end on a fixed stud 15a and having at its other end a toothed segment 16. The toothed segment 16 meshes with a pinion 17 rigidly secured to and, in the present instance, forming a part of a shaft 18 to which is rigidly secured a disk 19. In the present form of the apparatus this disk constitutes a part of an induction motor and is arranged between the pole pieces 20 of an electro-magnet, the coil of which is shown at 21. The magnet as a whole is pivotally mounted, as shown at 22, so that the pole pieces may be adjusted with relation to the periphery of the disk to vary the power which is applied to the disk and to control the speed at which the disk is driven. The direction of rotation of the disk by the electro-magnet is such that when the magnet is energized the supporting member 15 will be moved upwardly by the action of the pinion 17 on the segment 16. The circuit for the electro-magnet is so connected with the mercury tube switch that the upward movement of this switch, along with the supporting member, will break the circuit through the magnet, thus deenergizing the same and releasing the inertia wheel and supporting member for movement in a reverse direction. The supporting member and the mercury

tube switch are so mounted that when released they will move downwardly by gravity, the disk then functioning as an inertia wheel to regulate this downward movement. The weight of the mercury tube and its supporting member may be sufficient to return the same to the lowermost position but I prefer to supplement the weight of these parts, and to make the supplemental weight adjustable with relation to the supporting member so that it may be adjusted to vary the action of gravity on the supporting member and mercury tube. As here shown, an arm 23 is pivotally mounted on the supporting member 15 between the ends of the latter and is frictionally held in adjusted positions and this arm is provided at its lower or outer end with a weight 24. When this weight is moved toward the free end of the supporting member it will materially increase the weight of that structure and when it is moved toward the pivoted end of the supporting member it will decrease that weight, and if moved beyond the axis of the supporting member, as shown in dotted lines in Fig. 1, it will tend to counterbalance the weight of the supporting member and the mercury tube.

To avoid the shock or jar which would result from the sudden stopping of the supporting member and mercury tube I have provided a cushioning device which will yieldably check the movement of those parts in both directions. This cushioning device preferably comprises an endless band 25, such as a helical spring, which, in the present arrangement, is supported about the axis of the inertia wheel and the axis of the supporting member, the supports for the endless band being of such a diameter that the two stretches of the band will be spaced some distance apart. Rigidly connected with the supporting member 15 and, in the present instance formed integral therewith, is an arm 27 having at its free end a transverse finger 28 which extends between the upper and lower stretches of the yieldable band 25 and will contact with one or the other of those stretches as the tube supporting member approaches the limit of its movement in either direction, thus yieldably checking that movement. The contraction of the band after it has been engaged by the finger 28 will tend to impart a reverse movement to the finger and thus facilitate the initial movement of the tube supporting member in the opposite direction. Preferably the part or finger 28 is adjustable lengthwise of the arm 27 and of the slidable band 25 so as to vary the distance traveled by the finger upon each oscillation of the supporting member. As here shown, the finger is formed separate from the arm and is secured thereto in adjusted positions by means of a screw 29 which extends through a longitudinal slot 30 in the arm. The upper and lower portions of the yieldable band are normally spaced apart a uniform distance and by adjusting the finger it can be caused to engage one or the other of these portions of the band earlier or later in the movement of the tube supporting member. It is also desirable to provide means for positively checking the movement of the arm 27 and the supporting member after the finger has engaged the band. For this purpose I prefer to provide parts extending lengthwise of the band and forming stops, the two stops diverging in a direction away from the axis of the arm 27. In the present construction the supporting member and the inertia wheel 18 are mounted on a vertically arranged base plate 31. One end of the shaft of the inertia wheel is mounted in a bearing 32

mounted in the plate 31 and extending beyond that side thereof opposite the inertia wheel and the other end of the shaft is journaled in a bearing 33 carried by an arm 34 rigidly mounted in a terminal block 35 which in turn is rigidly secured to the base plate. The end of the stud 15a on which the supporting member is mounted projects beyond the rear side of the plate 31 and the endless band is mounted about collars 36 supported, respectively, by the projecting ends of the bearing 32 and of the stud 15a. The plate 31 is provided with an opening 37 through which the finger 28 extends and the upper and lower edges of this opening diverge away from the stud 15a and constitute the stops which positively limit the movement of the arm 27 and of the supporting member, after the finger has contacted with the resilient band. The size of the opening 37 is such that in all operative positions the finger 28 will engage the band before it engages the fixed stops. The angular arrangement of the fixed stops is such that with any adjustment of the finger on the arm 27 the arm will move the same distance and will occupy the same angular position when the finger engages the fixed stop. When the finger is positioned near that end of the arm remote from the axis the finger will engage the yieldable band earlier in the movement of the arm than it will when the finger is close to the axis of the arm and the band will be placed under greater tension, with the result that it will impart a quicker return movement to the arm, thus speeding up the action of the switch. The positive stops are not necessary to the operation of the device and are used only to prevent the segment from being moved out of mesh with the pinion.

Referring to Figs. 1 and 10 of the drawings it will be noted that the central contact 11 of the mercury tube switch is connected by a conductor 38 with a terminal 39 which in turn is connected to one side, 40, of the power line. The contact at one end of the tube, in the present instance the right hand contact 12, is connected by a conductor 41 with a terminal 42, which terminal is connected by a conductor 43 with one end of the magnet coil 21 and the other end of the coil is connected by a conductor 44 with a terminal 45 which is connected by a branch 46 with the other side, 47, of the power line. The terminal 42 is also connected by a conductor 48 with a lamp or group of lamps, as shown at 49, which lamp is connected with the line 47. The left hand contact 13 of the tube is connected by a conductor 50 with a terminal 51 which is connected by a conductor 52 with a second lamp, or group of lamps, as indicated at 53, and this second lamp is also connected with the line 47. It will be apparent, therefore, that when the mercury tube is in the position shown in Fig. 4 the circuit will be closed both through the electrically operated device or magnet coil 21 and through the first lamp 49. When the mercury tube is tilted in the other direction the circuit will be broken through the electrically operated device or magnet coil and through the lamp 49 and will be closed through the second lamp or group of lamps 53. This arrangement closes the circuits through the two lamps alternately and if it is desired merely to make and break the circuit through one lamp the connection with the contact 13 may be eliminated or a two contact tube may be employed, as shown in Figs. 6 and 8. I prefer to use a curved contact tube but this is not essential and a straight tube such as is 75

shown in Figs. 6 and 7 may be preferable for certain purposes.

When the mercury tube switch is inclined in the direction shown in Figs. 1 and 10 the circuit will be closed through the electrically operated device and upward movement will be imparted to the tube, thus tilting the same in the opposite direction. This tilting movement will result in the breaking of the circuit through the electrically operated device before the tube has completed its movement and the disk 18 will then function as an inertia wheel to assist in the completion of the movement of the tube and its supporting member. When the upward movement has been completed and checked by the cushioning device, the tube and its supporting member will move downward by gravity, but in so doing must overcome the inertia of the inertia wheel 19 and the action of this inertia wheel will cause the tube to move downwardly at a relatively slow and uniform speed. The tube will be tilted toward its first mentioned position sufficiently to again close the circuit through the electrically operated device before the tube completes its downward movement, but due to the action of the inertia wheel the downward movement of the tube will be continued against the action of the electrically operated device, which will then function as a brake to retard and finally stop the movement of the tube. After the downward movement of the tube has been stopped the electrically operated device must overcome the inertia of the inertia wheel before the tube again begins its upward movement, thus preventing the sudden starting or jerking of the tube. Due to the lag of the mercury in the curved tube the angular position to which the tube must be moved to open the circuit is substantially higher than the position to which it must be moved to close the circuit. Consequently the electrically operated device or motor will not begin to function until the tube has completed the major portion of its downward movement and will then continue to function until the tube has completed the major portion of its upward movement. The speed at which the mercury tube is tilted from one position to the other may be varied slightly by adjusting either the pole pieces of the electro-magnet or the weight 24 or by a proportionate adjustment of both these parts, but mainly by adjusting the finger on the arm of the cushioning device. By varying the power exerted on the supporting member to impart return movement thereto, as by adjusting the weight 24, with relation to the power of the electrically operated device, the timing of the switch may be varied, that is, the circuit may be retained closed for a longer or shorter period of time with relation to the period that it remains open.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a device of the character described, a mercury tube switch mounted for oscillating movement under electrical power controlled by its own circuits, and an inertia wheel operatively connected with said switch to control the frequency of said oscillations.

2. In a device of the character described, an inertia wheel, a mercury tube switch mounted

for oscillating movement in unison with said inertia wheel, and adjustable power means for varying the amplitude and frequency of said oscillations.

3. In a device of the character described, an inertia element, a mercury tube switch mounted for oscillating movement in unison with said inertia element, and opposed power means controlled by said switch and individually adjustable to vary the frequency of said oscillations and the relative duration of the on and off time of the circuits controlled by said switch.

4. In a device of the character described, a mercury tube switch, a supporting member for said switch pivotally mounted for movement in one direction by gravity, a weight connected with said supporting member and adjustable with relation thereto to vary the action of gravity thereon, electrically operated means for moving said supporting member in the other direction, said electrically operated means being adapted to be so connected with said mercury tube switch that the circuit through the same will be broken by a predetermined movement of said supporting member in the last mentioned direction, and an inertia element connected with said supporting member and adapted to impart further movement thereto after said circuit has been broken and to retard the reverse movement thereof by gravity.

5. In a device of the character described, a mercury tube switch, a supporting member for said switch pivotally mounted for movement in one direction by gravity, electrically operated means for moving said supporting member in the other direction, said electrically operated means being adapted to be connected in circuit with said mercury tube switch, said switch being so arranged that the circuit will be broken before said supporting member completes its movement in the last mentioned direction and will be closed before said supporting member completes its movement in the first mentioned direction, and an inertia element connected with said supporting member and arranged to complete the movement thereof after said circuit has been broken and to retard the initial movement thereof in both directions.

6. In a device of the character described, a circuit breaker and closer mounted for movement in one direction by gravity, electrically operated means for moving said circuit breaker and closer in the other direction, said electrically operated means being adapted to be so connected with said circuit breaker and closer that the circuit through the same will be broken by a predetermined movement of said circuit breaker and closer in the last mentioned direction, an inertia element connected with said circuit breaker and closer to impart further movement thereto in the same direction after said circuit has been broken and to control its movement in the other direction.

7. In a device of the character described, a circuit breaker and closer pivotally mounted for movement in one direction by gravity, electrically operated means for moving said circuit breaker and closer in the other direction, said electrically operated means being adapted to be so connected with said circuit breaker and closer that the circuit through the same will be opened by a predetermined movement of said circuit breaker and closer in the last mentioned direction, an inertia element connected with said circuit breaker and closer for movement therewith, a part connected

with said circuit breaker and closer for movement therewith, and a yieldable device having portions arranged on opposite sides of said part for engagement thereby when said circuit breaker and closer approaches the limit of its movement in either direction.

8. In a device of the character described, a circuit breaker and closer pivotally mounted for movement in one direction by gravity, electrically operated means for moving said circuit breaker and closer in the other direction, said electrically operated means being adapted to be so connected with said circuit breaker and closer that the circuit through the same will be opened by a predetermined movement of said circuit breaker and closer in the last mentioned direction, an inertia element connected with said circuit breaker and closer for movement therewith, a part connected with said circuit breaker and closer for movement therewith, a yieldable device having portions arranged on opposite sides of said part for engagement thereby when said circuit breaker and closer approaches the limit of its movement in either direction, and means for adjusting said part toward and from the axis of said circuit breaker and closer.

9. In a device of the character described, a circuit breaker and closer pivotally mounted for movement in one direction by gravity, electrically operated means for moving said circuit breaker and closer in the other direction, said electrically operated means being adapted to be so connected with said circuit breaker and closer that the circuit through the same will be opened by a predetermined movement of said circuit breaker and closer in the last mentioned direction, an inertia element connected with said circuit breaker and closer for movement therewith, a part connected with said circuit breaker and closer for movement therewith, a yieldable device having portions arranged on opposite sides of said part for engagement thereby when said circuit breaker and closer approaches the limit of its movement in either direction, means for adjusting said part toward and from the axis of said circuit breaker and closer, and fixed stops arranged on opposite sides of said part and diverging from the axis of said circuit breaker and closer.

10. In a device of the character described, a circuit breaker and closer pivotally mounted for movement in one direction by gravity, electrically operated means for moving said circuit breaker and closer in the other direction, said electrically operated means being adapted to be so connected with said circuit breaker and closer that the circuit through the same will be opened by a predetermined movement of said circuit breaker and closer in the last mentioned direction, an inertia element connected with said circuit breaker and closer for movement therewith, a part connected with said circuit breaker and closer for movement therewith, and an elastic band having upper and lower stretches arranged on opposite sides of and in the path of said part.

11. In a device of the character described, a circuit breaker and closer pivotally mounted for movement in one direction by gravity, electrically operated means for moving said circuit breaker and closer in the other direction, said electrically operated means being adapted to be so connected with said circuit breaker and closer that the circuit through the same will be opened by a predetermined movement of said circuit breaker and closer in the last mentioned direction, an inertia element connected with said circuit breaker and

closer for movement therewith, a part connected with said circuit breaker and closer for movement therewith, a vertical base plate on which said circuit breaker and closer and said inertia element are mounted, said plate having an opening therethrough, the upper and lower edges of which diverge, a part connected with said circuit breaker and closer for movement therewith and extending through said opening, and a cushioning device supported on that side of said base plate opposite said circuit breaker and closer and having resilient members arranged on opposite sides of and in the path of said part.

12. In a device of the character described, a circuit breaker and closer, an oscillating inertia element operatively connected with said circuit breaker and closer, and electrical power means connected through said circuit breaker and closer and adapted to maintain said oscillations, said parts being so constructed and arranged that the circuit will be closed at one point upon the movement of said switch in one direction and will be opened at a different point upon the movement of said switch in another direction.

13. In a device of the character described, a circuit breaker and closer mounted for tilting movement, electrically operated means for imparting initial movement to said circuit breaker and closer, said circuit breaker and closer being connected in circuit with said electrically operated means and arranged to break the circuit therethrough at the end of said initial movement, and an inertia wheel connected with said circuit breaker and closer to impart further movement thereto in the same direction after the circuit has been broken through said electrically operated means and to retard the initial movement thereof in the opposite direction.

14. In a device of the character described, a circuit breaker and closer mounted for tilting movement and movable in one direction by gravity, electrically operated means for imparting initial movement to said circuit breaker and closer in the other direction, said circuit breaker and closer being connected in circuit with said electrically operated means and arranged to break the circuit therethrough at the end of said initial movement, and an inertia element connected with said circuit breaker and closer to impart further movement thereto in the same direction after the circuit has been broken through said electrically operated means and to control its movement in the opposite direction.

15. In a device of the character described, a circuit breaker and closer mounted for tilting movement and movable in one direction by gravity, electrically operated means for imparting initial movement to said circuit breaker and closer in the other direction, said circuit breaker and closer being connected in circuit with said electrically operated means and arranged to break the circuit therethrough at the end of said initial movement, and an inertia element connected with said circuit breaker and closer to impart further movement thereto in the same direction after the circuit has been broken through said electrically operated means, and to retard the initial movement of said circuit breaker and closer by gravity in the reverse direction.

16. In a device of the character described, a circuit breaker and closer mounted for tilting movement and movable in one direction by gravity, electrically operated means for moving said circuit breaker and closer in the other direction, said circuit breaker and closer being connected in

5 circuit with said electrically operated means and arranged to break said circuit when it has been moved a predetermined distance by said electrically operated means and to close said circuit when it has been moved a predetermined distance, by gravity, and an inertia element connected with said circuit breaker and closer to retard the initial movement thereof in both directions.

10 17. In a device of the character described, a circuit breaker and closer mounted for tilting movement and movable in one direction by gravity, electrically operated means for moving said circuit breaker and closer in the other direction, said circuit breaker and closer being connected in circuit with said electrically operated means and arranged to break said circuit when it has been moved a predetermined distance by said electrically operated means and to close said circuit when it has been moved a predetermined distance 15 by gravity, and an inertia element connected with said circuit breaker and closer to retard the initial movement thereof by said electrically operated means, to complete the movement thereof after the circuit has been broken through said 20 electrically operated means, to retard the initial movement thereof in a reverse direction by gravity, and to regulate the speed at which said gravity movement is completed.

25 18. In a device of the character described, a circuit breaker and closer mounted for tilting movement and arranged to move in one direction by gravity, an electrically operated device to move said circuit breaker and closer in the other direction and connected in circuit therewith, and an inertia element connected with said circuit breaker and closer and arranged to cause the same to move at substantially a uniform speed in both directions.

30 19. In a device of the character described, a circuit breaker and closer mounted for tilting movement, an electrically operated device for actuating said circuit breaker and closer, and an inertia element operatively connected with said circuit breaker and closer and arranged to act 35 on the same separately from said electrically operated device to move said circuit breaker and closer in either direction.

35 20. In a device of the character described, a circuit breaker and closer mounted for tilting movement and movable in one direction by gravity, electrically operated means for moving said circuit breaker and closer in the other direction, said electrically operated means being so connected with said circuit breaker and closer 40 that the circuit through the same will be broken by the movement of said circuit breaker and closer in the last mentioned direction, an inertia wheel movable in both directions by inertia, and means for causing the movement of said wheel in 45 either direction to be transmitted to said circuit breaker and closer.

45 21. In a device of the character described, a mercury tube switch, a supporting member for said switch, pivotally mounted for movement in one direction by gravity, electrically operated means for moving said supporting member in the other direction, said electrically operated means being adapted to be so connected with said mercury tube switch that the circuit through 50 the same will be broken by the movement of said supporting member in the last mentioned direction, and a balanced inertia wheel operatively connected with said circuit breaker and closer to move the same in both directions independently 55 of said electrically operated means.

5 22. In a device of the character described, a mercury tube switch, a supporting member for said switch mounted for tilting movement, a balanced inertia wheel, a constantly operative connection between said inertia wheel and said supporting member to cause the same to move in unison, and electrically operated means for moving said supporting member and said inertia wheel in one direction, said electrically operated means being adapted to be so connected with said switch 10 that the circuit through the same will be broken by the movement of said supporting member by said electrically operated means.

10 23. In a device of the character described, a mercury tube switch, a supporting member for said switch mounted for tilting movement, an induction motor comprising a rotatable disk and an electro-magnet for rotating said disk, said disk being arranged to function as an inertia wheel when said electro-magnet is deenergized, 15 and means for operatively connecting said disk with said supporting member, said electro-magnet being adapted to be so connected with said switch that the circuit through the same will be broken by the movement of said supporting member in one direction and said disk caused to function as an inertia wheel to control the movement of said supporting member after said circuit has been broken.

20 24. In a device of the character described, a mercury tube switch, a supporting member for said switch pivotally mounted for downward movement by gravity, an induction motor comprising a rotatable disk and an electro-magnet for rotating said disk, said disk being arranged to 25 function as an inertia wheel when said electro-magnet is deenergized, and means for causing said supporting member to move in unison with said disk, whereby said electro-magnet when energized will impart upward movement to said 30 supporting member, said electro-magnet being adapted to be so connected with said switch that the circuit through the same will be broken by the upward movement of said supporting member.

35 25. In a device of the character described, a mercury tube switch, a supporting member for said switch pivotally mounted for downward movement by gravity, an induction motor comprising a rotatable disk and an electro-magnet for rotating said disk, said disk being arranged to function as an inertia wheel when said electro-magnet is deenergized, and means for causing said supporting member to move in unison with said disk, whereby said electro-magnet when energized will impart upward movement to said 40 supporting member, said electro-magnet being adapted to be so connected with said switch that the circuit through the same will be broken before said supporting member completes its upward movement and will be closed before said supporting member completes its downward movement.

45 26. In a device of the character described, a mercury tube switch, a supporting member for said switch pivotally mounted for downward movement by gravity, an induction motor comprising a rotatable disk and an electro-magnet for rotating said disk, said disk being arranged to function as an inertia wheel when said electro-magnet is deenergized, means for causing said supporting member to move in unison with said disk, whereby said electro-magnet when energized will impart upward movement to said 50 supporting member, said electro-magnet being 55 adapted to be so connected with said switch that the circuit through the same will be broken before said supporting member completes its upward movement and will be closed before said supporting member completes its downward movement.

adapted to be so connected with said switch that the circuit through the same will be broken by the upward movement of said supporting member, and a weight carried by said supporting member and adjustable to vary the action of gravity on said supporting member.

27. In a device of the character described, a mercury tube switch, a supporting member for said switch pivotally mounted for downward movement by gravity, an induction motor comprising a rotatable disk and an electro-magnet for rotating said disk, said disk being arranged to function as an inertia wheel when said magnet is deenergized, means for causing said supporting member to move in unison with said disk, whereby said electro-magnet when energized will impart upward movement to said supporting member, said electro-magnet being adapted to be so connected with said switch that the circuit through the same will be broken by the movement of said supporting member, an arm carried by said supporting member and adjustable with relation thereto, and a weight carried by said arm.

28. In a device of the character described, a circuit breaker and closer mounted for pivotal movement and having means acting normally to move the same in one direction, an electrically operated device connected in circuit with said circuit breaker and closer and adapted to act thereon to move the same in the opposite direction, and an inertia element connected with said circuit breaker and closer and arranged to retard the initial movement thereof in both directions.

29. In a device of the character described, a mercury tube switch, a supporting member for said switch pivotally mounted for movement in one direction by gravity and having at one end a toothed segment, an inertia wheel mounted for rotatory movement, a pinion rigidly connected with said inertia wheel, and having constantly operative engagement with said toothed segment, and electrically operated means for moving said supporting member in the other direction and so connected with said switch that the circuit through the same will be broken by a predetermined movement of said supporting member in the last mentioned direction and said inertia wheel will retard the initial movement of said supporting member by gravity.

30. In a device of the character described, a mercury tube switch, a tiltable supporting member for said switch having a toothed segment at one end thereof, an inertia wheel mounted for oscillatory movement, a pinion rigidly connected with said inertia wheel and having constant operative engagement with said toothed segment, and electrically operated means for moving said inertia wheel and said supporting member in one direction, said supporting member and said inertia wheel being movable in the other direction independently of said electrically operated means, said electrically operated means being adapted to be so connected with said switch that the circuit through the same will be broken when said supporting member is moved a predetermined distance in the first mentioned direction and said inertia wheel will retard the initial movement of

said supporting member in the last mentioned direction.

31. In a device of the character described, a circuit breaker and closer, an inertia wheel mounted for oscillatory movement and operatively connected with said circuit breaker and closer to control the movement thereof, and electrical power means connected through said circuit breaker and closer and adapted to maintain the oscillations of said inertia wheel.

32. In a device of the character described, a circuit breaker and closer, an inertia element mounted for oscillatory movement and operatively connected with said circuit breaker and closer, and yieldable reversing means arranged to act on said inertia element during the final portion only of its movement to gradually interrupt said movement, said reversing means being adjustable to regulate the frequency of the oscillations of said inertia wheel.

33. In a device of the character described, a circuit breaker and closer, an inertia element mounted for oscillatory movement and operatively connected with said circuit breaker and closer, and yieldable reversing means arranged to act on said inertia element during the final portion only of its movement in one direction to gradually interrupt said movement and during the initial portion only of the movement of said inertia element in the other direction to accelerate said initial movement.

34. In a device of the character described, a circuit breaker and closer, an inertia element mounted for oscillatory movement and operatively connected with said circuit breaker and closer, and yieldable reversing means arranged to act on said inertia element only while it is near the limit of its movement in one direction or the other, to gradually interrupt said movement and to accelerate the initial movement thereof in a reverse direction.

35. In a device of the character described, a mercury tube switch, an inertia wheel mounted for oscillating movement and operatively connected with said mercury tube switch to impart movement thereto, and electrical power means to maintain the oscillations of said inertia wheel, said mercury tube switch being adapted to control said electrical power means.

36. In a device of the character described, an inertia wheel mounted for oscillatory movement, and a mercury tube switch operatively connected with said inertia wheel for movement thereby and adapted to alternately close and open electrical circuits in unison with the oscillation of said inertia wheel.

37. In a device of the character described, an inertia element, a mercury tube switch mounted for oscillating movement in unison with said inertia element, electrical power means controlled by said switch for maintaining the oscillations of said mercury tube switch, and adjustable yieldable reversing means arranged to act on said inertia element only while it is near the limit of its movement in one direction or the other to gradually interrupt said movement and to vary the frequency of said oscillations.

GEORGE H. LELAND.

CERTIFICATE OF CORRECTION.

Patent No. 2,032,326.

February 25, 1936.

GEORGE H. LELAND

It is hereby certified that the above numbered patent was erroneously issued to "The Leland Electric Company, a corporation of Ohio", as assignee of the entire interest in said invention, whereas said Letters Patent should have been issued to the inventor, George H. Leland and The Leland Electric Company, a corporation of Ohio, said corporation being assignee of one-half interest only in said invention, as shown by the records of assignments in this office; and that the said Letters Patent should be read with this correction therein that the same may conform to the record of the case in the Patent Office.

Signed and sealed this 31st day of March, A. D. 1936.

Leslie Frazer

(Seal)

Acting Commissioner of Patents.
